DESIGN FOR A LABEL

Edmond Opler, Hinsdale, Ill., assignor to Siren
Mills Corporation, Chicago, Ill., a corporation of Illinois

Application April 8, 1937, Serial No. 68,628

Term of patent 14 years

To all whom it may concern:

Be it known that I, Edmond Opler, a citizen of the United States, residing at Adams Road and Thirty-fifth Street, in the city of Hinsdale, county of DuPage, and State of Illinois, have invented a new, original, and ornamental Design for a Label, of which the following is a specification, reference being had to the accompanying drawing forming a part thereof.

The drawing is a face view of a label having no appreciable thickness embodying the design.

I claim:

The ornamental design for a label, as shown and described.

EDMOND OPLER.
